UNITED STATES PATENT OFFICE.

NEALE RANSOM, OF JERSEY CITY, NEW JERSEY.

ERASER.

1,178,944.

Specification of Letters Patent.

Patented Apr. 11, 1916.

Application filed November 20, 1912. Serial No. 732,411.

To all whom it may concern:

Be it known that I, NEALE RANSOM, a citizen of the United States, residing at Jersey City, in the county of Hudson and State 5 of New Jersey, have invented certain new and useful Improvements in Erasers, of which the following is a specification, reference being had therein to the accompanying drawings, which form a part thereof.

10 My invention relates to erasers, and more particularly to a type of rubber eraser, especially adapted for eradicating the work done on a typewriting machine.

The main object of the invention is to 15 provide an eraser of this character which will act more rapidly in removing typewritten matter from a paper than the ordinary rubber typewriter eraser, without like-lihood of wearing through or cutting the 20 paper.

A further object is to provide an eraser 25 of this character, wherein the operative surfaces are so arranged as to permit the operation of the eraser in a small area, as when removing but one or two letters, as well as in a larger area, as when removing an entire line.

A still further object is to provide an 30 eraser comprising a plurality of independent rubber elements united and maintained in the proper relation to each other to secure the desired effect of the eraser when used, while at the same time permitting the substitution of new rubbers as required. 35 And a still further object is to provide an eraser of this character which may be economically produced, and used in connection with rubber typewriter erasers now extensively manufactured.

40 The invention consists primarily in a rubber typewriter eraser embodying therein a plurality of narrow rubber elements, spaced apart and parallel with each other, and connecting means whereby said elements are 45 held in a fixed relation to each other so as to be capable of simultaneous or independent application to the paper; and in such other novel features of construction and combination of parts as are hereinafter set forth and described, and more particularly pointed out in the claims hereto appended.

50 Referring to the drawings: Figure 1 is an elevation of an eraser embodying my invention; Fig. 2 is a projection thereof in the 55 direction indicated by the arrow in Fig. 1;

Fig. 3 is a detail view of a single friction element entering into the article; and Fig. 4 is a detail view of a detachable clip or yoke, adapted for use in connection with two elements as shown in Fig. 3. 60

Like letters refer to like parts throughout the several views.

In actual practice, I have found that a device made in accordance with my invention embodying disk-like rubber elements, 65 gives highly satisfactory results, and in the accompanying drawings, I have illustrated my invention in connection with elements of this character.

In the practice of my invention, I employ 70 two narrow rubber erasing elements, each of which is reinforced, excepting adjacent to the edge thereof, with metallic plates, connecting means coöperating with said reinforcing plates being provided so that said 75 elements may be secured in a fixed position relative to each other, preferably two such elements being employed. The connecting means and the reinforcing plates, space these elements slightly apart, and the manner of connecting these elements holds them in parallelism with the operative edges thereof occupying substantially the same plane perpendicular to the parallel planes which the elements occupy. By this construction both elements can be simultaneously 80 applied to the paper, but a slight interval is afforded between the action of the elements upon any portion of the paper, which 85 interval is defined by the space between the 90 elements.

In actual practice, I have discovered that by this arrangement, matter may be erased without likelihood of cutting the paper, while at the same time making a clean 95 erasure, in fact more clean than can be secured by the use of a single erasing element, and with less disturbance of the surface of the paper. Furthermore, I have discovered that when two such erasing elements are used, with the expenditure of the same or less energy, the time required to 100 erase a line of typewritten words with my improved eraser is but one third as great as that required with but a single element. If 105 the number of elements in my eraser were increased, and the increased number could be handled conveniently, there would be a still further saving of time and energy.

In the form of the invention shown in 110

the drawings, I have shown at *a* and *b* two rubber disk elements, mounted upon metallic spindles *c d* carrying reinforcing plates *e f* and *g h* respectively, these plates being 5 of a diameter less than that of the disks *a b*. At *i* I have shown a yoke plate, the arms of which are bifurcated so as to straddle the spindles *c d*, these arms being of a thickness to readily enter between the reinforcing plates *f* and *g* respectively and the adjacent rubber elements. The dimensions 10 of this yoke are preferably such as to bring the loop thereof close to the edge of the reinforcing plates, and all parts thereof, 15 within said plates, so as to prevent any portion of this yoke projecting within the operative range of the rubber disks. The top of 20 this yoke is also formed in a curve coinciding with the periphery of said reinforcing disks. This yoke is preferably made detachable from the spindles *c d* and the plates *f g* in order to permit the use of the same yoke with different rubber elements, if desired.

25 In using my eraser, the plates *e h* are grasped firmly between the thumb and forefinger, and the edges of the disks *a b* brought into contact with the paper and moved axially of said disks. If the same 30 pressure be exerted upon the paper through the disks, the pressure applied to the paper by either disk will be materially diminished from that which would occur with a single disk, while at the same time both disks operate 35 simultaneously with a slight dwell between the action of one disk and that of the other upon the same portion of the paper.

As I have heretofore stated, the combined 40 action of both elements in an eraser made in accordance with my invention is not a mere duplication of the action of one erasing element, but there is an actual and material increase in efficiency by the use of my eraser over the use of a single eraser for 45 twice the period. This may be due to the fact that when one erasing element acts upon a given point of the paper, the action of the element in advance thereof has already removed a large portion of the ink 50 from the paper, or the surface of the paper containing this ink; it may also result from the fact that there is a double action upon the paper before the fibers have been so disturbed by a reversal of the movement of the 55 eraser as to have protected any of the superficial ink thereon; or it may be due to the fact that the slight dwell between the rubber members permits the raised fibers to reset slightly so as to permit the second element to come into intimate contact with the 60 paper carrying the ink.

Whatever the explanation, in actual practice I have found that with an eraser made in accordance with my invention, a line of 65 typewritten matter may be cleanly erased in

about four seconds without cutting the paper or removing an excess portion thereof, and that with an ordinary single eraser of the same quality and in the same condition as either of the erasing elements of my 70 eraser, about twelve seconds are required, and frequently the paper is worn completely through or is so reduced in thickness as to be untidy. Furthermore, by reason of the decreased pressure in the application of each 75 erasing element to the paper, and the lessening of the period during which each such element is operative, the life of these elements is considerably prolonged.

By the use of narrow disks spaced apart, 80 the operative surface of each element is reduced in area to a point where it will readily act upon the paper and at the same time, if it is desired to remove or eradicate a single 85 letter, or a small group of letters, by merely tilting the eraser so as to bring only one of the elements into engagement with the paper, the operative range of the eraser may be made to conform to small spaces upon 90 the paper.

It is not my intention to limit the invention to the precise details of construction shown in the drawings, it being apparent that such may be varied without departing from the spirit and scope of the invention so 95 long as at least two rubber elements are employed, the operative portions of which are spaced apart, and these elements occupy parallel planes.

Having described my invention, what I 100 claim as new and desire to have protected by Letters Patent, is:—

1. A rubber typewriter eraser embodying 105 therein a plurality of similar narrow flat circular rubber elements which have flat parallel sides and a narrow operative circular edge, said elements being closely juxtaposed with their flat sides parallel and concentric with each other, and means arranged adjacent the center of and intermediate 110 said elements respectively whereby they are connected and spaced apart, said means including a reinforcing metallic plate carried by each of said elements whereby 115 said elements respectively are so supported adjacent the center thereof that the edges thereof are capable of simultaneous or independent application to the paper.

2. A rubber typewriter eraser embodying 120 therein a plurality of similar narrow flat circular rubber elements, each having parallel flat sides, and a narrow operative edge, said elements being closely juxtaposed with their flat sides parallel and concentric with each other, reinforcing metallic plates arranged substantially centrally of each element, and upon opposite sides thereof, said 125 disks being extended radially of said elements sufficiently to support the elements while leaving the portion thereof adjacent 130

the operative edges unsupported, and a metallic member coöperating with the metallic plates of and arranged between the adjacent elements presented toward each other whereby by said member will be contained between said plates and within said operative edges and said elements are held in a fixed relation to each other with their edges spaced apart so as to be capable of simultaneous or independent application to the paper.

3. A rubber typewriter eraser embodying therein a plurality of similar narrow flat rubber elements, each having substantially parallel flat sides and a narrow operative edge arranged with their flat sides parallel with each other and their narrow edges upon substantially the same plane, reinforcing metallic plates upon opposite sides of each of said elements, and a metal yoke 20 adapted to be removably inserted between the metal plates of adjacent elements presented toward each other and said elements respectively whereby said elements are held in a fixed relation to each other with their 25 edges spaced apart so as to be capable of

simultaneous or independent application to the paper.

4. A rubber typewriter eraser, embodying therein a plurality of narrow rubber elements, spaced apart and parallel with each other, each of said elements being provided with metallic plates upon opposite sides thereof and a spindle securing said plates adjacent to said elements, and a yoke having bifurcated ends adapted to enter between one of said plates of each element and the element, and to straddle said spindles, whereby said elements are held in a fixed relation to each other so as to be capable of simultaneous or independent application to the paper.

In witness whereof, I have hereunto affixed my signature, in the presence of two subscribing witnesses, this 18th day of November, 1912.

NEALE RANSOM.
